WOVEN FABRIC REINFORCEMENT

Freeman W. Fraim, West Barrington, R. I., assignor to International Braid Company, a corporation of Massachusetts

Application May 13, 1944, Serial No. 535,421

8 Claims. (Cl. 244—145)

1

This invention relates generally to the reinforcing of a woven fabric and especially to reinforcing a parachute fabric. It has particular reference to the manufacture of reinforcing braid to increase the load-carrying capacity of the woven sail or canopy of a parachute.

All textile materials in being loaded have a definite elongation characteristic dependent upon the type of fiber used and the construction of the fabric. When two dissimilar constructions of fabric each made of a different fiber are tightly joined as by sewing, the problem of causing each fabric to sustain its own proportion of the load is complicated by many factors.

Heretofore, it has been practically impossible to sew a highly dimensionally unstable braid to a more stable woven fabric and have both fabrics or members exhibit the same elongation characteristics before rupture. Even so, it has been considered desirable to sew a coreless unstable braid to a parachute formed of woven cloth for reinforcing the same.

One of the objects of this invention is to provide a braided cord which when sewed onto a woven cloth will have an equal elongation to the cloth so that both units will elongate equally as a whole.

Another object of this invention is to provide the reinforcing braid of novel construction simplifying the problem of balancing the stretch characteristics of the reinforcing member and of a woven cloth.

Another object of this invention is to provide a braided fabric with a known and controllable elongation that can be easily manipulated by unskilled sewing machine operators in attaching the same to a woven cloth so as to have the same elongation as the woven fabric.

Another object of this invention is to provide a parachute in which the maximum strength of the reinforcing braid is obtainable thus resulting in a stronger parachute and yet one which may be made light in weight and occupy a minimum volume.

Another object of the invention is to provide a braid which will lie generally flat and free from twisting.

More specifically, this invention is to provide a braided fabric which will have a core or warp to definitely provide a reference point as to elonga-

2

tion of the braided fabric which may be used in properly attaching or sewing the braided fabric to the woven fabric.

With these and other objects in view, the invention consists of certain novel features of construction, as will be more fully described and particularly pointed out in the appended claims.

In the accompanying drawings:

Fig. 1 is a plan view of a fragmental portion of a braided fabric constructed in accordance with this invention;

Fig. 2 is an elevation of a parachute open and showing my reinforcing braid such as shown in Fig. 1 attached to the canopy thereof;

Fig. 3 is a greatly enlarged view illustrating the position of a core or warp in the fabric of Fig. 1;

Fig. 4 is a sectional view taken substantially on line 4—4 of Fig. 2;

Fig. 5 is a diagrammatic view illustrating a portion of the serpentine path of the yarns of the fabric about the core or warp.

In proceeding with this invention I provide a braid woven on a usual form of braiding machine and of generally known construction except that one or more members are located in the braid for controlling its axial stretch and which are incorporated in the braid as cores or warp ends. Preferably these are incorporated at diametrically opposite points in a tubular braid which serves to cause the tube to lay flat and maintain itself in a single plane.

The selection of the materials as to stretch or elongation prior to rupture is important. The axial control members are themselves constructed by twisting or by fiber selection and pre-stretching to have a fixed elongation from rest to rupture equal to the elongation of the material of the woven fabric to which the finished reinforcing braided cord is to be sewed. The braided cord is then constructed of selected yarns with a definite package and tension such that its elongation from the point at which the axial control members are taut to rupture will be the same as that of the axial control members. These axial control

members therefore contribute to the strength of the cord as a whole and provide a reference point from which the elongation of the entire cord is definite and known. This reference point is that point of elongation where the warp ends become taut through the application of a certain range of

tension. This tension may be easily applied by hand when sewing occurs. Working tension at or beyond the amount to produce this condition is all that is needed to properly handle the finished cord and fabric. A braid constructed in the foregoing manner can readily be handled in a sewing operation where it is applied to a woven cloth by sewing. It is only required that sufficient tension be applied to make the warp ends become taut since a considerable increase of tension would be required to elongate the warp ends beyond this point.

With reference to the drawings, the braid which I construct is made upon a regular tubular braider with the carriers winding in and out of the serpentine raceways to leave the yarns as 10 and 11 as fragmentally shown in Fig. 5 in a tubular formation. At diametrically opposite points extending up through posts in two of the diametrically opposite quoits of the machine, there are cores or warps which are fed up to the maypole of the machine and there assembled in the braid in a locked relation.

The axially controllable members are designated 15 and 16, as shown in Figs. 1 and 3, and are strands of twisted yarn composed of fibers so selected or prestretched as to have a fixed elongation from hand tautness to rupture equal to the elongation of the woven material 18 to which the finished reinforcing cord is to be sewed.

The braided yarns 25 are provided from a plurality of packages on the braider carriers which move in and out through the serpentine pathways of a braider so as to braid their yarns one about the other and also about the cores 15 and 16. By this arrangement the cores 15 and 16 are locked in the braided fabric as cores and provided axially extending controllable members. The elongation of the braid may be controlled by changing the picks per inch.

The yarns which are used in braiding as at 25 may be of many different materials, such for instance as cotton, rayon, or silk, I have found it satisfactory to use rayon yarn which is composed of a plurality of yarns laid side by side and woven as a group in generally flat form one about the other. The number of yarns and the twist given each will be selected for the strength characteristics desired.

In Fig. 2 I have illustrated a parachute consisting generally of a sail or canopy 17 composed of a plurality of segments 18 sewed together along gore lines 19 each shaped substantially along the area of a segment of the surface of the sphere. The fabric in each one of the segments 18 is woven from a light-weight material of strong construction. The sewing or gore lines 19 serve to reinforce the canopy along the direction of their extent. At the edge of the canopy 20 where the gore lines meet this edge shroud lines 21 are attached which come to a common point 22 to support a load through the part designated generally 23. In order to reinforce this canopy the braided cord described above designated generally 24 is sewed around the canopy at right angles to each of the gores 19. The braid will thus be provided in concentric circles at 24, 24', and 24'', the latter 24'' being at the edge 20 of the canopy. In performing this sewing operation the canopy is held hand taut and the braid which I provided is held hand taut and these two are then sewed together, both under the same hand tautness.

The controllable members 15 and 16 serve to provide a definite reference point for the braided cord so that the braided cord may be made hand

taut at this certain point as a limit in sewing it in position. For this reference point it is known that the characteristics of the braid by reason of prior selection, picking and so forth will be a certain definite amount which will be equal to the elongation from this reference point to rupture of the woven cloth. Thus when the two are sewed together under the same tautness from this reference point it is known that both members, materials or units will elongate the same from this reference point to rupture and thus each will add to the final product the maximum strength which it possesses.

The parachute may be packed into a very small space and yet be very strong for its weight due to the above construction.

I claim:

1. The method of reinforcing a woven fabric which consists in selecting a strand having a fixed elongation from a certain tautness to rupture equal to the elongation of the woven fabric from a definite tautness to rupture, braiding about said strand a cord formed of yarns so selected as to material and so tensioned that the elongation from the point at which said strand is taut to rupture will be the same as that of the strand and attaching said cord to the woven fabric to be reinforced with both under their predetermined tautness as a reference point.

30 2. A woven fabric having a braided cord attached thereto, said fabric and cord both with the same fixed elongation from a certain tautness to rupture, and an axial member in said cord serving as a reference point for determining the stretch of said cord at said tautness.

35 3. A woven fabric having a braided cord attached thereto, said fabric and cord both with the same fixed elongation from a certain tautness to rupture, and an axial member in said cord 40 serving as a reference point for determining the stretch of said cord at said tautness, said member also having the same elongation to rupture from said tautness.

45 4. A woven fabric having a braided cord attached thereto, said fabric and cord both with the same fixed elongation from a certain tautness to rupture, and a pair of axial members in said cord serving as a reference point for determining the stretch of said cord at said tautness.

50 5. A woven fabric having a braided cord attached thereto, said fabric and cord both with the same fixed elongation from a certain tautness to rupture, and a pair of axial members in said cord serving as a reference point for determining the stretch of said cord at said tautness, said members also having the same elongation to rupture from said tautness.

60 6. A woven fabric having a tubular braided cord attached thereto, said fabric and cord both with the same fixed elongation from a certain tautness to rupture, and a pair of axial members in said cord located at diametrically opposite points for controlling the stretch of said cord at said tautness.

65 7. A parachute having a canopy with circular reinforcing cords attached thereto, said canopy and cords both having the same circular elongation from a certain tautness to rupture and an axial member in said cord controlling the stretch of said cord at said tautness.

8. A parachute having a canopy of woven fabric with circular reinforcing cords sewed thereto, said canopy and cords both having the same elongation in the direction of said cords from a certain tautness to rupture and an axial member

in said cord controlling the stretch of said cord at said tautness.
